Ms. 625

Peter Seibert of Pittsburgh, Pa., assignor to

Alexander Bradley of same place.

Letters Patent No. 625 - Dated Jan. 31st, 1854.

The schedule referred to in these Letters Patent, & making part of the same is

To all whom it may concern: Be it known that I, Peter Seibert, of Pittsburgh, Alleghany County, State of Pennsylvania have invented or produced a new & useful design for Cooking Stoves, & I do hereby declare the following to be a full & exact description of the same reference being had to the accompanying drawing, & to the letters of reference marked thereon, to wit; letter B, being a perspective view of the stove. — (That I claim as my invention and desire to secure by Letters Patent, is the ornamental design for a stove, as represented in the annexed drawing).

Witness: N. Buckmaster,
I am. Wm. Vanhook.

Peter Seibert.
